Fredrick Goodell and Thomas W. Harvey of Ramapo New York
Letters Patent.

The Schedule referred to in their Letter Patent and making part of the same containing a description in the words of the said Fredrick Goodell and Thomas W. Harvey themselves of their Improvement in the Board Loom for weaving Bristle frames and for other purposes.

To all to whom these presents shall come. Weit known that we Fredrick Goodell and Thomas W. Harvey of Ramapo in the County of Rockland and State of New York have invented a new and useful Improvement in the power loom for the purpose of weaving bristles hair or whale bone splints into a web of cotton linen or silk or yarn used for make Stocke and the foundation of Stocke called Stocke frames, and also for weaving such like materials or straw into a web for other purposes than Stocke or Stocke frames and the following is a full and exact description thereof. First to a common power loom having a suitable frame, yarn and cloth beams, take up and stop motions, lathe and shuttle crank and cam shafts, harrows, or heads, heads cams, and picker pictures, driving pulleys, a pair of cog wheels, connecting cranks, and cam shafts, cam and crank arms which & roller &c. The same substantially as are in general use in the common power loom for weaving plain cloth with the exception of comprising the width of this loom to twenty inches or there abouts between the frames, we have suspended an apparatus for placing the Bristles into the web by forceps, after being placed on each side of the web back of the race board between the range of the shuttle and the rod. Secondly an apparatus for measuring the length of Stocke frames by stopping the bristle forceps, after weaving 1 3/4 inches (or less) of shuttle cloth, and then starting in motion again after weaving 3 1/2 inches (or more or less) of plain cloth without bristle filling. Thirdly, an apparatus for changing the movement of the picker from a shot of the shuttle with thread filling every stroke to one in two strokes of the shuttle while weaving bristle cloth, to wit, a shot of thread filling and a shot of bristles alternately but picker, every beat of the lathe while weaving plain cloth without bristles, for a description of which reference is had to the drawing annexed at &c. Fig 1. Bristle forceps or pincers attached to the lathe and move

with it (see pinions on sectional drawing Fig 3.) B.B. Fig 1. Bristle board attached to the leather. F.F. Fig 1. two sides to which the bristle board are attached and extend down to the bottom of the leather swordy being connected, shank and worked on the transverse cam. U.U. Fig 2. D.D. Fig 1. levers working in the transverse and straight grooves (opened by switch a) at one end and connected at the other end with the bristle forceps and sustained at the fulcrum by an arm E.E. attached to the leather. G.G. Fig 1. switch stands.

G fig 1. is a transverse cam on front shaft. I Fig 2. the end of the cam is depressed $\frac{3}{4}$ of an inch $\frac{1}{4}$ of the circumference of the cam. The remainder of this cam is full working against the ^{front of the} plunger f. and gives motion to switch a. A similar cam is placed on the end of said shaft on the opposite side of the loom. H Fig 1. is a similar cam on the back or cam shaft with this difference. The depression is one half the circumference of the cam, its use the same but being twice the speed of cam G. on front shaft it changes the switches, two to one and directs the movement of the bristle forceps accordingly. L Fig 1. is a spring fastener having two holes to fit upon a pin in stand R. one of the holes directs the plunger f. to the cam H. the other hole directs the plunger f. to cam G. A Fig 1. is a connecting lever lever between plunger f. and switch a and is attached to a stand R fastened to the outside frame place. The lever is thrown out from the framed top by a spring M. Fig 1. is an index cam. A similar as at the other end of the shaft. C. Fig 1. is an index roller over which the web passes and is in front the length of a stock frame O. Fig 1. is a top roller of metal to secure the cloth from slipping on roller O. P. Fig 1. is an arm held up to cam M by a smart spring, (not shown in the drawing) back of the outside frame and moves upright at 2.2.2. Q Fig 1. is a rod affixed to arm P. on the other end of said rod is a dog fixture which when the arm P. drops into the indentation in the cam M. is brought forward outside of lever C and drops it and serves to hold open the straight groove of switch a. and stops the motion of the bristle forceps and determines the length that bristles are to be woven into the stock frame. R Fig 1. is a changing cam having a sliding piece so constructed as to open a straight and a zig-zag groove and

working the shuttle loose. S. working includes P. which rotates connects by sliding rods t. to. fig 2. with the picker arms xx xx xx. UU. Fig 2. are cams on to shuttle p. in the shape of heart. having their eccentric placed on the shaft. the one moves from the other and working against the ends of slides H.F. Their use is to banish the shuttle boxes up and down in order to distribute the picks of the shuttle properly uniformly out of the shuttle boxes. V Fig 2 is a ratchet wheel on the same shaft and is moved by the stationary spring 12. fastened to the lower end rail and falling into the notches of the ratchet wheel when the latter is thrown back. and moving the transmission shaft when the latter beats up. W. Fig 2 is a shaft called transverse shaft fastened by bearings to the lower part of the lathe. M. Fig 2. is a slide bolt in the shaft S. and reaches to a cross bar X. which passes through the end of the bolt and a notch in the shaft. U. Fig 1. is a support fastened to the inside frame. and the shuttle stand and propped up to allow the crank arms to play freely. C. Fig 2. is an extra shaft connected to the back cam shaft by cog wheels ii and is two to one slower than the cam shaft. W. Fig 1. is an arm affixed by a pivot on the inside of the outer frame and is held in by spring A. and connected with bar C and slide bolt. W. C. Fig 1. is an arm affixed to arm P and connects to cl. bar C and serves to draw out the bolt W. when the arm P drops into the indentation in the index cam M. and opens the straight groove arm R. Fig 2. h. fig 1 is a latch held forward towards the arm C by a spring on stand Q and is connected with the arm R by the rod M. by passing through a hole in the lower end of latch h. and is secured by a screw nut. When the arm P drops into the indentation in cam M the latch falls back of the arm C and holds it till the arm P is thrown back to fireplay of the cam M by the passing of the web. when done the spring C slides the bolt W and opens the zig zag groove in cam R. Fig 2. and changes the motion of the shuttle from one to two to act. a shot of the thread shuttle every other beat of the lathe.

WORK AND OPERATION. This loom comprehends what we term a plain and complex loom. By taking off the screw nut on rod M. Fig 1. which connects it with latch h. the loom is plain in which case the slide bolt W is constantly forced out by latch h. and the straight groove is held open and the shuttle is kept going every beat of the lathe. By connecting them the complex

loom is constituted whereby the zig-zag groove above described is opened and the shuttle motion is changed from a pick every beat, to one every other beat of the lathe during the space the loom is weaving bristles into the web and then going to a pick every beat of the lathe while the shuttle grasps an alternate. The zig-zag groove is formed to open $3\frac{1}{4}$ of the circumference of the cam H. the remainder of the circle is stationary so that this shaft being two to one slower in movement than the back or cam shaft. moves the shuttle P, Fig 2. which connects with the two picker cams H.H. by the slide rods L.L. in a manner for the cams to miss the shuttle treadles alternately first one and then the other. The picker cams are securely affixed to the slide rods L.L. and slide upon a feather affair in the cam shaft. The cams marked 1 and 2 have their eccentricities alike and are directly opposite to the one marked 3. The shuttle is a. going on a pivot and when thrown inward opens transverse grooves into which the lever D works and throws forward the forceps. When thrown outward a straight groove is opened and the forceps are at rest. The movement of the shuttle is indicated by the cams G.G. and H.H. Fig 1. When the plunger F is set to cam G the straight groove of the shuttle is open $3\frac{1}{4}$ and the transverse groove is open $\frac{1}{4}$ of the time. By reversing this cam G. to the one on the opposite end of shaft 2, fig 2 a motion will be given to the right and left hand forceps alternately missing one pick of bristles every other beat of the lathe. or if the cams G are set to agree with each other both forceps, Fig 2 at the same time at every fourth beat of the lathe. When the plunger F is set to cams H the same effect is produced in every beat with the exception of doubling the frequency of the picks of the forceps the cam shaft being two to one in speed of the shaft 2. Fig 2.

Operation of the Bristle forceps - When the lathe is thrown back and the forceps are shot through the web into the shuttle box, the button a. Fig 3 strikes a propelling piece and turns the button from its seat against the lower arm of pinion marked v. Fig 3 when the spring part of the forceps marked y shot and seize the bristles whereupon on the return of the lathe to beat up, the forceps are brought back with the bristles till then held have reached the opposite selavage of the cloth when the lower arm of the forceps rises on to a regulating piece and forces them open when they snap the bristles

which are caught by croping the shade of the web at that instant the forceps being carried still farther back until the ballow is turned into its seat again by striking against said regulating piece. That part of the forceps marked w. Fig. 3. lies into the shade piece y and serves as a standard for the forceps and protects their points from entangling in the web by projecting beyond the point of the forceps. The slide piece z is seated upon the rear board of the lattice and is connected with lever D. Fig. 1. The forceps and the shuttle pass through the web at the same instant and in different ranges from each other in such a manner as not to interfere with each other, each bristle box is set opposite to its respective forceps a space of two inches being open to receive them the capacity of the boxes being $\frac{3}{8}$ of an inch thick and as high as desirable, and as long as the bristles, the bristles are kept down by placing metal weights of the calibre of boxes over them. What we claim as new and dearby Patent is. First the manner of working the bristle forceps and their connexion including their combination with the shuttle a. a. and transverse cam g and h. Secondly the manner of traversing the bristle boxes. Thirdly the manner of changing the motion of the shuttle and its connexion with the index arm. M. Fourthly the manner of measuring off the length of the stock frame, by the operation of the loom as combined with the changing motion of the shuttle in claim third and in connexion with the index roller and cam with the stoprod Q which stops the shuttles. Fifthly the use of two pair of bristle forceps to a loom a pair on either side of the web, by which the bristles are placed butts and flanks alternately into the web. Sixthly the manner of protecting the points of the bristle forceps by the projecting piece marked w. Fig. 3. it being longer and broader than the points of the forceps. And Lastly to the general arrangement of the above claimed parts in its adaptation to a common power loom.
